UNITED STATES PATENT OFFICE.

JUSTICE C. IRWIN, OF MINNEAPOLIS, MINNESOTA, ASSIGNOR, BY MESNE ASSIGNMENTS, TO STANTON HOME SAFE COMPANY, OF CHICAGO, ILLINOIS, A CORPORATION OF ILLINOIS.

LOCKING DEVICE.

Application filed June 1, 1925, Serial No. 34,044. Renewed May 14, 1928.

This invention relates to new and useful improvements in locking devices, but more particularly relates to such mechanisms of the type adapted for use on small devices such as coin banks, to lock the closures thereto.

An object of the invention is to provide a lock mechanism comprising a locking member of unitary structure adapted to be mounted in a closure and co-operating therewith to lock said closure to a container.

A further object of the invention is to provide a one-piece locking member having a plurality of spring-actuated locking bolts or projections thereon which are adapted to be moved into and out of locking position by means of a key-member inserted therein.

The particular object of the invention therefore is to provide an improved locking device particularly adapted for use on coin banks, by the use of which the cover or closure therefore may readily and quickly be mounted upon and demounted from the bank in a minimum amount of time.

Other objects of the invention will appear from the following description and the accompanying drawings and will be pointed out in the annexed claims.

In the accompanying drawings there has been disclosed a structure designed to carry out the objects of the invention but it is to be understood that the invention is not confined to the exact features shown as various changes may be made within the scope of the claims which follow.

In the accompanying drawings forming part of this specification:

Figure 1 is a perspective view of a conventional form of coin bank showing the closure locked thereto by the improved locking device;

Figure 2 is an enlarged detail sectional view of the bank, partially broken away, to show how the closure is locked thereto;

Figure 3 is a cross sectional view on the line 3—3 of Figure 2, showing the one-piece locking member in locking position;

Figure 4 is a similar view showing the locking member in unlocking position;

Figure 5 is a perspective view of the improved locking member removed from the closure; and

Figures 6 and 7 show locking members of a modified construction.

In the selected embodiment of the inven-

tion here shown, for purpose of disclosure, there is illustrated a conventional form of coin bank comprising a tubular casing 11 having a coin slot 12 at one end thereof through which the coins are inserted into the bank. The construction of the body portion of the bank and the means provided therein for preventing the coins from being removed from the bank through the slot 12, forms no part of the present invention and therefore need not be shown and described in detail.

An important feature of this invention resides in the novel means provided for locking the closure 13 to the open end of the casing 11. Coin banks such as the one above described, usually have a cover or closure demountably secured to one end thereof so that access may be had to the interior thereof for the removal of the coins after the bank has been filled or partially filled. The construction of this cover must be such that it may readily and conveniently be removed from the bank in a minimum amount of time and may as readily be secured or locked thereto after the bank has been emptied of its contents.

It is a common practice with many savings banks to distribute small coin banks among their depositors in order to stimulate and increase the habit of saving. These banks are therefore periodically returned to the bank by the depositors, and their contents removed therefrom and credited to the depositors' accounts. It is therefore essential that the covers or closures for such coin banks be so constructed that the bank tellers may quickly unlock them from the bank and as quickly replace them thereon in order that there will be no loss of time in so doing. The particular locking device featured in this invention is particularly designed to meet the above requirements as it may quickly be removed from and replaced upon the savings bank by the use of a key-member retained by the teller.

Referring to Figures 2, 3 and 4, it will be noted that the closure 13 is provided with an annular flange 14 adapted to be inserted into the open end of the casing 11, (see particularly Figure 2). A locking member 15, preferably constructed of one-piece as shown, is mounted within the annular flange 14 of the closure 13. This locking member is provided with a plurality of flexible arms 16 having locking lugs or projections 17 terminally

- formed thereon which are seated in guide apertures 18 provided in the annular flange 14 and are adapted to outwardly project therethrough as shown in Figures 2 and 3.
- 5 The open end of the casing 11 is preferably rolled as shown in Figure 2 to provide an inwardly projecting annular flange or lip 19 adapted to cooperate with the projections or lugs 17 to lock the closures 13 to the casing.
- 10 when mounted therein as shown in Figure 2. Each lug 17 is also provided with a beveled face 21 adapted to engage the annular flange 19 when the cover is inserted into the casing 11, thereby causing the lugs to be inwardly moved to the position shown in Figure 4, until the cover reaches the position shown in Figure 2, after which the arms 16 will outwardly force the lugs into locking position as shown in Figures 2 and 3.
- 15 A key-slot 22 is provided in the central portion of the locking member 15 and is adapted to register with a similar slot or opening 23 provided in the closure 13, when the locking member 15 is in locking position as shown in Figures 2 and 3. When the key-member 24 is inserted through the opening 23 in the closure and into the slot 22 in the locking member, the locking member may be partially rotated from the position shown in
- 20 Figure 3 to that shown in Figure 4, wherein it will be seen that the lugs 17 are contracted or inwardly moved out of contact with the inwardly projecting flange 19 of the casing 11 so that the closure may readily be removed therefrom. The inward movement of the lugs 17 is effected by means of the inclined faces 20 thereof engaging the ends of the guide slots 18 when the locking member is rotated. (See Fig. 4). It is also to be noted
- 25 by reference to Figure 4 that the particular construction and shape of the flexible arms 16 of the locking member is such that when the locking member is contracted or moved into unlocking position as shown in Figure 4, all of the arms will be moved into contact with one another before the lugs 17 are moved entirely out of the openings 18 in the flange 14 of the closure; thereby providing means for preventing the locking member from accidentally becoming separated from the closure when the latter is removed from the bank.
- 30 The above construction also provides a stop for limiting the amount of rotation of the locking member within the closure 13.
- 35 From the foregoing, therefore, it will readily be seen and understood that by the employment of this novel one-piece locking member in conjunction with the closure of such a coin bank the locking mechanism therefore will be greatly simplified. The locking member 15 may be stamped or punched from suitable sheet metal so that it may be manufactured in large quantities at a very low cost. It will also be noted that the locking device, as a whole, comprises only two parts,

namely, the closure and the locking member 15 mounted therein, which is operable by means of the key-member 24 shown in Figure 1.

A stop lug 25 is preferably provided on the annular flange 14 of the cover 13 adapted to engage an inwardly projecting lug 26 formed in the casing 11, to lock the closure 15 against rotation when the key-member 24 is being rotated to unlock the closure from the casing. When it is desired to remove the closure 13 from the casing 11, the key-member 24 is inserted through the key-slot 23 in the cover and into the corresponding slot 22 in the key-member 15, after which it is rotated and a slight outward pull imparted thereto which will remove the closure from the casing. The closure may be mounted upon and locked to the casing without the use of the key-member by simply inserting the flange 14 thereinto and slightly pressing the finger against the closure which will cause the lugs 17 to be inwardly moved to the position shown in Figure 4 until the ends thereof pass the annular flange 19, after which they will snap into locking position as shown in Figures 2 and 3, by the tension of the arms 16.

Figures 6 and 7 show locking members of modified constructions. The structure shown in Figure 6 comprises a central disc 20 having a key-slot 27 provided therein. In this construction the arms 16 and lugs 17 are constructed of wire suitably formed and each having one end secured to the disc 20 as shown, thereby forming in effect a one-piece structure which will function in a manner similar to that shown in the previous figures. The structure shown in Figure 7 is similar to that shown in Figure 6 with the exception that it is made of a single piece of wire having its central portion coiled to form a slot or opening 28 adapted to receive the key-member 24.

In the preferred construction shown in Figures 3, 4 and 5, the locking member is shown as having four locking lugs 17. It is to be understood that the number of such lugs may be varied, as desired, without departing from the invention, the primary object of the invention being to provide a locking member of unitary structure, thereby greatly simplifying the construction of the lock mechanism with a resultant decrease in the cost of manufacture. The construction of this novel locking device is also such that it can not easily be rendered inoperative, thereby providing such a device which is well adapted for use on such structures as coin banks.

I claim as my invention:

1. A locking device for a container cover comprising a locking member adapted to be mounted upon the cover for relative movement thereon, said member having a plurality of flexible arms adapted to be moved into locking engagement with the container walls,

means for moving said arms and each arm having an inclined face cooperating with means on said cover whereby, when the locking member is relatively rotated by said means, said arms will yield radially and become disengaged from said container walls.

2. A locking device for a container cover comprising a locking member mounted in the cover and adapted for relative movement therein, said locking member having a plurality of flexible arms integrally formed thereon, lugs on said arms adapted to be moved into locking engagement with the container walls, means for relatively rotating said arms and each lug having an inclined face adapted to engage the cover whereby, when the locking member and arms are actuated by said means, said lugs will be moved out of locking engagement with said container walls.

3. A locking device for a container cover including a locking member and a supporting means therefor, said locking member be-

ing of unitary structure and comprising a hub having a plurality of flexible arms and lugs thereon adapted for locking engagement with the container walls, and said lugs having beveled faces adapted to engage said container walls and flex said arms and allow said cover to be seated on said container, without the use of a key.

4. A locking device for a container cover comprising a locking member adapted for movement therein, said locking member having a plurality of flexible arms integrally formed thereon, lugs on said arms adapted to be moved into locking engagement with the container walls, means for moving said arms by a key, and each lug having an inclined face adapted to engage the cover whereby, when the locking member and arms are actuated, said lugs will be moved out of locking engagement with the container walls.

In witness whereof, I have hereunto set my hand this 18th day of May 1925.

JUSTICE C. IRWIN.
